UNITED STATES PATENT OFFICE.

CHARLES ROZELL, OF HUTCHINSON, KANSAS.

DESIGN FOR A HITCH-REIN LOOP.

SPECIFICATION forming part of Design No. 33,165, dated September 4, 1900.

Application filed July 24, 1900. Serial No. 24,723. Term of patent 14 years.

To all whom it may concern:

Be it known that I, CHARLES ROZELL, a citizen of the United States, residing at Hutchinson, in the county of Reno and State of Kansas, 5 have invented and produced a new and original Design for a Hitch-Rein Loop, of which the following is a specification.

The invention relates to a new and original design for a hitch-rein loop; and it has for its object to provide a design of this character which will be both useful and ornamental.

The leading feature of the design consists in the design forming the subject-matter of the accompanying illustration.

5 In the drawings, Figure 1 is a perspective view of a hitch-rein loop, showing my new and original design. Fig. 2 is a sectional view of the same.

Referring to the drawings, 1 designates a hitch-rein loop consisting of a substantially segmental or semicircular base-plate 2 and a

transversely-disposed oblong loop or frame 3, having short parallel sides 4 and a connecting end piece 5, arranged at right angles to the sides 4. The rectangular loop or frame 25 is arranged at an angle to the plane of the semicircular base-plate, and it extends therefrom at the ends of the straight edge thereof, forming an obtuse angle. The base-plate 2 presents flat upper and lower faces and its 30 inner straight edge is arranged parallel with the end piece 5 of the oblong loop or frame.

What I claim is—

The design for a hitch-rein loop herein shown and described.

In testimony that I claim the foregoing as my own I have hereto affixed my signature in the presence of two witnesses.

CHARLES ROZELL.
